UNITED STATES PATENT OFFICE.

CLAUDE SIEBRING, OF GEORGE, IOWA.

GATE.

No. 863,231.

Specification of Letters Patent.

Patented Aug. 13, 1907.

Application filed February 9, 1907. Serial No. 356,655.

To all whom it may concern:

Be it known that I, CLAUDE SIEBRING, a citizen of the United States, residing at George, in the county of Lyon and State of Iowa, have invented a new and useful

5 Gate, of which the following is a specification.

The invention relates to improvements in gates.

The object of the present invention is to improve the construction of swinging gates, more especially that shown and described in Patent No. 805,032, granted to me Nov. 21, 1905, and to provide inexpensive and efficient means for positively opening and closing the gate at a distance from either side of it, and for securely locking the gate in its closed position and for retaining the same in its open position until positively closed by 10 the operating mechanism.

With these and other objects in view, the invention consists in the construction and novel combination of parts hereinafter fully described, illustrated in the accompanying drawings, and pointed out in the claims 20 hereto appended; it being understood that various changes in the form, proportion, size and minor details of construction, within the scope of the claims, may be resorted to without departing from the spirit or sacrificing any of the advantages of the invention.

25 In the drawings:—Figure 1 is a perspective view of a gate, constructed in accordance with this invention and shown partially open. Fig. 2 is a side elevation of the same, the gate being closed. Fig. 3 is a detail view, illustrating the construction of the latch mechanism.

30 Fig. 4 is a detail sectional view, illustrating the construction for locking the slidable eye at the inner or rear end of the loop-shaped guide of the gate. Fig. 5 is a detail view, illustrating the arrangement of the guides for the flexible connection of the operating mechanism.

35 Fig. 6 is a detail sectional view, illustrating the manner of mounting the oscillatory gate actuating lever.

Like numerals of reference designate corresponding parts in all the figures of the drawings.

1 designates a swinging gate, provided at its inner 40 or rear end with upper and lower eyes 2 and 3, which are slidable vertically on upper and lower pintles 4 and 5, having angularly bent terminals 6. The angularly bent terminals of the pintles pierce an upright or post 7, and are secured to the same by nuts, or other suitable 45 fastening devices. The lower pintle, which is arranged at an inclination, extends upwardly and outwardly, and the upper pintle is oppositely inclined being extended upwardly and inwardly. By this construction, the gate, when moved vertically in opening by the means 50 hereinafter described, has its lower portion moved outwardly from the hinged post, and its upper portion moved inwardly towards the same thereby throwing the gate at an angle, which assists the opening movement and serves to retain the gate in its open position.

55 The gate is swung horizontally and lifted vertically

by means of an oscillatory lever 8, fulcrumed at its lower end in a substantially U-shaped bracket or bearing 9, which is provided with a depending pivot 10, mounted in a bearing of a stub post 11 and retained therein by a cap plate 12. The lower end of the oscillatory lever 8 is connected with the bearing bracket by a horizontal pivot 13, which pierces the sides of the bracket and the lower end of the lever. By means of the vertical and horizontal pivots of the bracket, the oscillatory lever is adapted to swing and is also capable 60 of rotary movement to enable an arm 14 of the upper end of the lever to swing substantially in a horizontal plane. The arm 14, which is arranged substantially at right angles to the body portion of the lever, is preferably supported by an inclined brace 15, and it is provided at its outer end with an eye 16, which slides on a loop-shaped guide 17 of the gate. The loop-shaped guide, which is arranged at an inclination, extends downwardly and rearwardly from its outer end, and its terminals, which are bent at an angle, are suitably secured to the top of the gate.

The oscillatory lever is provided at an angle, formed by the arm and the body portion of the lever, with an eye 18 to which is secured one end of a flexible connection 19, which passes through a guide 20. The guide, which is arranged horizontally, is provided with supporting arms 21, having inner and outer portions arranged at an angle to each other and receiving grooved pulleys 22 and 23. The attaching portion of the guide is secured to a horizontal bar 24, which is supported 80 by the post or upright 7 and by a post or upright 25, arranged a suitable distance from the post or upright 7 at one side of the gate, and extending above the horizontal bar, which is located at the upper end of the said post or upright 7. The upper end of the flexible connection 19 is connected with the inner ends of a pair 85 of operating levers 26 and 27. The operating lever 26 is fulcrumed at a point between its ends on the post or upright 25 at the upper end thereof, and the other operating lever 27 is fulcrumed on an arm or bar 28, arranged at an inclination and extending upward from the post or upright 7 and from the proximate end of the bar 24, which projects horizontally beyond the post or upright 7. The operating levers are provided at 90 their outer ends with suitable handles 29, arranged in a convenient position to be grasped by a person on horseback, or in a vehicle. When the gate is closed, the eye 18 of the oscillatory lever is located in advance of the guide 20, and when the gate is opened, the said eye 18 is carried to a point in rear of the guide 20, so that an 95 upward pull on the flexible connection 19 will operate to swing the oscillatory lever forwardly to close the gate.

The gate is provided at its free end with a rigid projecting latch 30, located near the top of the gate in position 110

tion to engage a keeper 31, mounted on a small gate 32, which is rigidly held in a closed position by a fastening device or latch, forming the subject-matter of a companion application, executed by me of even date here-
5 with. The small gate dispenses with a latch post, and the keeper, which is secured at its lower end to the upper portion of the small gate, is provided between its ends with an angular bend, which off-sets its upper portion from the small gate to provide a recess into
10 which the latch 30 drops, when the gate closes. The upper end of the keeper is provided with an outwardly extending inclined lip 32^a for guiding the latch 30 to the said recess.

When either of the levers 26 and 27 is operated to
15 open the gate, the gate is lifted by the oscillatory lever, which is drawn rearwardly, and the eye 16 is carried to the rear end of the loop-shaped guide, and it is locked in such position by means of a vertically movable locking bar 33, guided on the gate and movable vertically
20 across the space between the guide and the top bar of the gate. The locking bar has a reduced upper engaging end 34, which passes through a perforation 35 of the top bar of the gate 1, and the lower end of the locking bar is provided with an eye 36, which is connected
25 with a crank bend 37 of a longitudinal rock shaft 38. The rock shaft 38, which extends longitudinally of the upper portion of the gate, is journaled in suitable bearings of the same and the crank bend 37 is located at the rear portion of the said shaft. The front end of the
30 shaft is provided with a crank arm 39, arranged within a loop 40 and projecting beyond the gate 1, and adapted to engage the front bar of the gate 32, or other latch supporting means. The inner end of the rock shaft receives a coiled spring 41, which holds the locking bar
35 33 normally extended, and the loop 40 forms a stop for limiting the movement of the crank arm 39. When the longitudinal rock shaft 38 is free to move, it is automatically rotated by the coiled spring 41 to move the locking bar 33 upwardly. This operation takes
40 place in the opening movement of the gate 1, when the front end of the latter is carried away from the gate 32 and when the gate 1 closes, the crank arm 39 is carried into engagement with the gate 32 to rotate the shaft 38 against the action of the spring 41 to move the locking
45 bar 33 downwardly. The crank arm 39 is arranged at an inclination, when the gate is open, and the eye 16 is confined at the rear end of the guide 17 by the locking bar, and when the gate closes, the crank arm of the rock shaft strikes against the front bar of the gate
50 32 and the rock shaft is rotated by such contact to withdraw the locking rod from engagement with the eye 16 to permit the latch 30 to drop to the bottom of the recess of the keeper, whereby the gate will be securely held in its closed position. The locking device for
55 holding the eye at the rear end of the guide is automatically operable to engage and release the said eye. The coiled spring 41, which actuates the rock shaft 38,

has one of its terminals connected with the same, and the other terminal is suitably connected to the gate.

Having thus fully described my invention, what I 60 claim as new and desire to secure by Letters Patent, is:-

1. The combination with a support, of upper and lower pintles, the upper pintle being inclined upwardly and inwardly and the lower pintle being inclined upwardly and outwardly, a gate slideable vertically on the pintles, which, when the gate is raised, move the bottom of the gate outwardly from the support and carry the upper portion of the gate inwardly towards the said support and operating mechanism for opening and closing the gate, said operating mechanism being provided with means for raising the gate in the opening movement thereof, whereby the gate is tilted. 65

2. The combination of a swinging gate provided with a guide, a lever provided with means slideable on the guide 70 for connecting it to the gate, and automatically operable means for locking the slideable means at one end of the guide.

3. The combination of a vertically movable horizontally swinging gate having a guide, an oscillatory gate actuating lever provided with means slideable on the guide for connecting it to the gate, and an automatically operable spring actuated locking device for holding the slideable means at one end of the guide. 80

4. The combination of a vertically movable horizontally swinging gate having a guide, an oscillatory lever slideably connected with the guide, a locking rod mounted on the gate and arranged to lock the lever at one end of the guide, and a rock shaft connected with the locking rod for operating the same. 85

5. The combination of a horizontally swinging gate, a gate actuating lever slideably connected with the gate, a locking rod arranged to hold the lever against movement on the gate, a rock shaft connected with the locking rod and provided with a projecting crank element. 90

6. The combination of a horizontally swinging vertically movable gate, an actuating lever slideably connected with the gate, a locking rod arranged to hold the lever against movement on the gate, a shaft having a crank element connected with the rod and provided with a second 100 crank element extending beyond the gate, and a spring for holding the locking rod in its engaging position. 95

7. The combination with a keeper and means for supporting the same, of a vertically movable horizontally swinging gate provided with a latch for engaging the keeper, an actuating lever slideably connected with the gate, a locking member for holding the lever against movement on the gate, and a spring actuated rock shaft connected with the said member and having a crank element arranged to engage the keeper supporting means. 110

8. The combination with a vertically movable horizontally swinging gate, of an actuating lever slideably connected with the gate and arranged to lift the same in the opening movement thereof, means for automatically holding the lever against movement on the gate to maintain 115 the said gate in an elevated position during the opening and closing movements, and means for releasing the lever at the end of the closing movement of the gate. 116

In testimony, that I claim the foregoing as my own, I have hereto affixed my signature in the presence of two 120 witnesses.

CLAUDE SIEBRING.
